UNITED STATES PATENT OFFICE.

MARK W. STOLL, OF NEWARK, NEW JERSEY, ASSIGNOR TO NOVALIS WATCH COMPANY, INC., OF NEW YORK, N. Y., A CORPORATION OF NEW YORK.

DESIGN FOR A WATCH CASING.

Application filed September 19, 1924. Serial No. 10,834. Term of patent 7 years.

To all whom it may concern:

Be it known that I, MARK W. STOLL, a citizen of the United States, residing at Newark, in the county of Essex and State of New Jersey, have invented a new, original, and ornamental Design for a Watch Casing, of which the following is a specification, reference being had to the accompanying drawing, forming a part thereof.

Fig. 2 is a rear view of the same; and Fig. 3 is an edge view of the same.

I claim:

The ornamental design for a watch casing as shown.

MARK W. STOLL.
